UNITED STATES PATENT OFFICE.

THEODORE G. CRANE, OF CHICAGO, ILLINOIS.

SMOKER FOR CURING MEATS.

Application filed April 10, 1925. Serial No. 22,044.

This invention relates to an oil gas heater and wood smoke producer for meat curing establishments.

It is an object of this invention to provide 5 an improved portable meat smoker operated on liquid fuels. To accomplish these results, a gas generating type of oil burner is provided to insure clean combustion of the fuel and to provide the heat necessary to 10 maintain the proper temperature in the smoke house in addition to the slow combustion of sawdust to produce the desired wood smoke. It is essential to the production of cured meats of the proper flavor that 15 no trace of soot, smoke, or odor be produced during the combustion of the primary fuel.

It is also an object of this invention to provide an improved and simplified type of oil gas smoker adapted to easy control by 20 unskilled operation.

Other and further important objects of 25 this invention will be apparent from the disclosures in the specification and the accompanying drawings.

This invention (in a preferred form) is 30 illustrated in the drawings and hereinafter more fully described.

On the drawings:

Figure 1 is a side elevation of a device 35 embodying the features of this invention.

Figure 2 is a front or end elevation thereof.

Figure 3 is a top plan view thereof.

Figure 4 is a section on the line 4—4 of 40 Figure 1.

Figure 5 is a section on the line 5—5 of Figure 4.

Figure 6 is a section on the line 6—6 of 45 Figure 4, showing the burner or arrangements.

Figure 7 is an enlarged fragmentary section on the line 7—7, showing detail of the combustion air inlets.

Figure 8 is an enlarged fragmentary section on the line 8—8, showing the adjustable air outlets.

Figure 9 is a section on the line 9—9 of 50 Figure 8.

As shown on the drawings:

A boxlike casing 10 is provided with suitable legs 11 and a sliding drawer like bottom 12 to carry the burners. The top 13 of the box is formed as a sliding tray to receive the sawdust which is burned to produce the 55 smoke for curing the meats. This tray is provided with a series of apertures 14 cen-

trally arranged in a longitudinal direction and covered by a hood 15 allowing outflow of the highly heated products of combustion from the burner box to ignite and burn the 60 sawdust with the maximum production of smoke. The production of smoke depends on a restricted oxygen supply, and by using the products of combustion from the heating elements to supply the oxygen for the combustion of the sawdust, a pungent and effective smoke is produced.

Air inlets 16 in the bottom of the box are provided with hoods 17 directing the inflowing air against the sides of the box for 70 proper diffusion before passing to the burners. Suitable sliding draft doors or vents 18 are provided along the sides of the box below the top to regulate or distribute the heat uniformly through the smoke house. 75 The sawdust tray may also be slid back a suitable distance to provide a direct outlet to the room to increase the heating effect.

The front of the burner drawer 12 carries an oil manifold 19 supplied through a flexible line 20 from a storage tank. This manifold is provided with individual burner supply outlets 21 with regulating valves 22, and also with a bleeder outlet 23 for draining the fuel line and for removing entrained 85 air when first filling the fuel system.

A series of gas generating burners 24 are arranged on burner bases 25 having a trough 26 adapted to receive the bottom part 27 of the burner, the trough serving to receive 90 liquid fuel, the burning of which heats the generating burner to a temperature sufficient to convert the liquid fuel into a gas. The burner itself comprises an inverted V-shaped generating section 28 adapted to be heated 95 to convert the fuel into a gas and terminating in the plugged bottom member 27 which has an orifice positioned beneath the apex of the generating section so that the burning gas plays over the whole generating section.

After filling the fuel system and releasing the entrained air through the bleeder outlet, the various burner valves 22 are opened long enough to fill the trough 26 in the burner bases with liquid fuel. This fuel preferably kerosene, is then ignited and the heat therefrom serves to start the generator sections of the burners to function. It is to be understood that the regulating valves are 105 closed during the warming up operation and when the burners are hot enough the valves 110

are slowly opened. If the burner orifices squirt a liquid stream the generator sections are not hot enough and the regulating valves are again closed. The smoke house heat 5 can be regulated by adjustment of the draft doors and by sliding the sawdust pan back.

I am aware that many changes may be made, and numerous details of construction 10 may be varied through a wide range without departing from the principles of this invention, and I therefore do not purpose limiting the patent granted hereon, otherwise than necessitated by the prior art.

I claim as my invention:

15 1. A meat curing apparatus comprising a casing, a pan thereabove adapted to receive a smoke producing material, oil gas generating burners within said casing adapted to burn the smoke producing material and to 20 heat the surrounding atmosphere, and means for adjusting the proportion of heat directed towards heating the atmosphere.

25 2. In a device of the class described, a casing, a drawer therein, vaporizing oil burners mounted on said drawer, a plurality of adjustable outlets in said casing for heated air, and a pan resting on said casing adapted to receive a smoke producing substance.

30 3. In a device of the class described, a

casing, a drawer therein, vaporizing oil burners mounted on said drawer, a plurality of adjustable outlets in said casing for heated air, a receptacle for smoke producing material forming the top of the casing, and 25 outlets for the heated products of combustion through said pan and said smoke producing material.

4. In a device of the class described, a casing, a sliding top therefor adapted to receive combustible smoke producing material, 40 a hood extending above said sliding top and having outlets for the products of combustion within said casing, said outlets being adjacent the surface the sliding top, and oil 45 burners within said casing.

5. In a device of the class described, a casing, a sliding top therefor adapted to receive combustible smoke producing material, a hood extending above said sliding top 50 and having outlets for the products of combustion within said casing, said outlets being adjacent the surface the sliding top, a drawer in said casing, and a plurality of individually controlled oil burners mounted 55 on said drawer.

In testimony whereof I have hereunto subscribed my name.

THEODORE G. CRANE.
